ADJUSTABLE MUFFLER

Edward W. Bottum, 9357 Spencer, Brighton, Mich.
Filed Sept. 10, 1962, Ser. No. 222,411
7 Claims. (Cl. 181—57)

The present invention relates to an adjustable muffler, and more particularly to a muffler for use in reducing pulsations and noise in systems in which air or other gas flows, the muffler being adjustable to be effective in different systems.

The muffler of the present invention may be used in any system in which a gas must be exhausted, such as from the operation of a gasoline or other engine or in connection with the compressor of a refrigeration system. The muffler may be used on either the suction or discharge side of a compressor or engine. However, the greatest effect from the muffler is normally achieved by installing it in the discharge line of a compressor or the exhaust line of an engine. The muffler is particularly useful in refrigeration systems where the elimination of noise is highly important.

The use of mufflers has, of course, been quite common in the past. However, the use of conventional prior art mufflers has to some extent been unsatisfactory in systems where high quality muffler performance is necessary. The configuration of the muffler is very important with reference to the performance of the muffler. The pressure drop and orifice conditions in the muffler can significantly affect muffler performance. Muffler performance is particularly important in refrigeration systems where the pressure drop through the muffler and the amount of noise suppression in the muffler are very important. A muffler may perform satisfactorily with one refrigeration compressor at a given suction pressure or load condition. However, if the operating conditions of the compressor are changed, or if the muffler is utilized in a different system, resulting in a different pressure drop through the muffler, the performance of the muffler may be quite unsatisfactory.

It is, therefore, an object of the invention to provide an adjustable muffler.

Another object of the invention is to provide a muffler which, when installed in a system, may be adjusted to vary the orifice opening within the muffler with a consequent variation to the resistance to flow in the muffler.

A further object of the invention is to provide a muffler having a plurality of baffles with orifice openings which are adjustable externally of the muffler without the escape of gas from the system.

Other objects of this invention will appear in the following description and appended claims, reference being had to the accompanying drawing forming a part of this specification wherein like reference characters designate corresponding parts in the several views.

In the drawing:

FIGURE 1 is a side elevational view in section of one embodiment of an adjustable muffler according to the present invention;

FIGURE 2 is a side elevational view in section of another embodiment of the invention;

FIGURE 3 is a side elevational view in section of still another embodiment of the invention;

FIGURE 4 is a side elevational view in section of a further embodiment of the invention; and

FIGURE 5 is a partial sectional view of the FIGURE 4 embodiment showing the muffler in an adjusted position.

Before explaining the present invention in detail, it is to be understood that the invention is not limited in its application to the details of construction and arrangement of parts illustrated in the accompanying drawing,

2

since the invention is capable of other embodiments and of being practiced or carried out in various ways. Also, it is to be understood that the phraseology or terminology employed herein is for the purpose of description and not of limitation.

Referring to FIGURE 1, it will be seen that the muffler 10 comprises a casing including a hollow cylindrical member 12 having end closures 14, 16 secured thereto. The closures 14, 16 may be secured to the member 12, as may be other components of the muffler, by any suitable method such as brazing.

The closures 14, 16 have openings 18, 20 in which are secured, respectively, inlet fitting 22 and outlet fitting 24. The inlet and outlet are suitable attached to conduits (not shown) in the system in which the muffler is used.

Secured within the member 12 are a plurality of spaced apart cup-shaped baffle plates 26. Each baffle plate 26 is provided with a small opening 28 adjacent the lower portion of member 12 for the flow of oil through the muffler. Oil is, of course, present in the gases of a refrigeration system.

A relatively large opening 30 is provided centrally of each plate 26. The openings 30 are provided for the flow of gas through the muffler.

Extending axially through the openings 30 is a shaft 32. The shaft 32 carries a plurality of spaced apart closure members 34, one for each plate 26 and positioned adjacent each opening 30. The closure members 34 are provided to permit variation of the orifices formed by openings 30 of the plates 26 and adjacent closures 34.

The shaft 32 to which the closure members are secured is axially adjustable to permit varying the distance of the closure members from the baffle plate 26. As will be noted, the inner end of the shaft is slidably received through an opening 36 in a guide member 38 which is secured to the end closure 14. A support and sealing member 40 is provided at the opposite end of the muffler. The member 40 is received in an opening 42 of the end closure 16 and is secured thereto. The member 40 has an internally threaded axial opening 44 therethrough. The shaft 32 has a threaded portion 46 which is threadingly received in the opening 44. As will be noted, a portion of the shaft extends exteriorly of the muffler and has a wrench engageable head 48 for threading the shaft in the member 40. A packing gland 50 is provided to seal the opening 44 against escape of gas from within the muffler. The gland 50 is conventional in structure, comprising a nut 52 which is threadingly received in threaded portion 53 of opening 44. An annular sealing element 54, fabricated from asbestos-graphite or the like, is positioned within opening 44 and is wedged into sealing engagement with the shaft 32 and angular wall portion 56 by the nut 52.

An internally threaded cap 58 is received on external threads 60 of the member 40. The cap 58 serves to further seal the muffler so that any gas which does escape by the sealing element 54 is further restricted from escaping from the system. The cap 58 is, of course, removed when it is desired to adjust the shaft 32.

In operation of the muffler 10, the muffler is installed in a system by attachment of suitable conduits to the inlet and outlet 22, 24. The cap 58 is then removed, and the shaft 32 is threaded into or out of the member 40 to move the closure elements 34 closer to or further from the plates 26. This adjustment varies the size of the orifices through the plates 26. The extent of the adjustment, which is made while the system is in operation, is determined by the noise level of the muffler. That is, the shaft 32 is adjusted axially to achieve the lowest possible noise level.

Variation in the size of the orifice openings varies the

resistance to the flow of gas. This is of importance in muffler performance. Additionally, changing the position of the closures will vary the deflection of the gas and change the turbulence characteristics of the gas which are also important factors in muffler performance.

An alternate construction is illustrated in FIGURE 2. In the FIGURE 2 construction, a separate internal guide and support member for the shaft 62, such as the member 38, is not used. Instead, the shaft 62 extends through an opening 64 provided in the first baffle plate 66. The baffle plate 66 has an opening 68 adjacent to the lower portion of the casing 70. The opening 68 serves as a path for both the oil and gas which enter the muffler. The remaining baffle plates 72, 74 are substantially identical to the baffle plates 26 provided in the FIGURE 1 construction. The shaft 62 is provided with closure elements 76, 78 which act to vary the orifices through the openings 80, 82 in the plates 72, 74 as previously described. The shaft 62 is axially adjustable in the same manner as the shaft 32 of the FIGURE 1 embodiment.

Another construction is illustrated in FIGURE 3. In the FIGURE 3 construction, a tube 84 extends through openings 86 in baffle plates 88. The tube 84 has a plurality of peripherally spaced openings 90 at the juncture of each baffle plate 88. The openings 90 serve as a path for gas by the baffle plates 88.

The size of the orifice through the openings 90 is made adjustable by the provision of a rod 92 which slidably extends into the tube 84. As will be noted, the rod 92 has a portion 94 of reduced diameter adjacent each of the openings 90. The rod 92 has a threaded portion 96 of reduced diameter which is threadingly engaged in member 98. The structure of member 98 is identical with the member 40 of the FIGURE 1 embodiment.

As will be appreciated, the rod 92 may be moved axially within the tube 84 by threading the reduced portion 96 thereof into or out of the member 98. Axial movement of the rod 92 in either direction will act to reduce the orifice created by the openings 90 and the portions 94 of reduced diameter of the rod 92. Thus, the muffler of FIGURE 3 is adjustable in a manner similar to the FIGURE 1 embodiment.

The muffler structure illustrated in the various figures may be modified as desired to suit particular conditions. For example, only the first or second baffle plates nearest the outlet or inlet may be made adjustable. Additionally, the closures on the adjustable shaft may be in any shape or configuration to provide desired muffler characteristics.

Once the muffler of the present invention is installed, it may be quickly adjusted to the system to provide best performance. This eliminates the time and expense involved in installing different mufflers to achieve top performance. Additionally, an adjustable muffler provides an almost infinite range of adjustment which is not possible by using different mufflers.

FIGURE 4 illustrates a further modification of the muffler. In this embodiment, baffle plates 100 form compartments 102 within the casing 104. A tube 106 extends through openings 108 in the baffles. Gas flows into tube 106 from inlet compartment 110 and flows therefrom into outlet compartment 112. Annularly spaced openings 114 are provided in tube 106 in each compartment 102. The openings 114 permit the flow of gas into and out of the compartments 102 as the pressure of the input gas in the tube 106 varies to thus accomplish the muffling function. A second tube 116 is rotatably mounted within the tube 106. The tube 116 is manually rotated to different positions within tube 106 by actuation of a shaft 107 which is connected to the tube by a spider 109 and extends through a gas-tight fitting 111 to terminate exteriorly of the casing. Tube 116 is provided with annularly spaced openings 118 which are in annular alignment with the openings 114. As will be appreciated, the tube 116 may be rotated to different positions as shown in

FIGURE 5 wherein the openings 114, 118 are not in exact registry to thereby vary the size of the orifices formed by the openings and thus alter the muffler characteristics to suit different circumstances.

Having thus described my invention, I claim:

1. An adjustable muffler comprising a casing having an inlet and an outlet, a plurality of spaced apart baffles in the casing, said baffles having openings therethrough for the passage of gas through the muffler, a shaft extending into the casing from the exterior thereof, sealing means between the shaft and casing forming a gas-tight seal, a cap over the external portion of the shaft to effect an additional gas-tight seal, said shaft having means providing at least one closure element adjacent one of the openings of a baffle, said closure being related to the opening of the adjacent baffle to form an orifice through the baffle, said shaft being axially movable by actuation thereof exteriorly of the casing to adjust the position of the closure to thereby adjust the size of said orifice.

2. A device as claimed in claim 1 and further characterized in that a closure element is provided on the shaft for each baffle, axial movement of the shaft being effective to adjust the orifice formed by each baffle opening and related closure element.

3. An adjustable muffler comprising a casing having an inlet and an outlet, a plurality of spaced apart baffles in the casing, said baffles having registering openings therethrough for the passage of gas through the muffler, said casing having an opening therein, a shaft extending from a point exteriorly of the casing through said casing opening and through the baffle openings, sealing means on the casing opening to effect a gas-tight seal, a cap over the external portion of the shaft to effect an additional gas-tight seal, a plurality of spaced apart closure elements provided on the shaft, each of said closure elements being adjacent one of the baffle openings, each of said closures being related to the opening of its respective adjacent baffle to form an orifice through the baffle, said shaft being axially movable by actuation thereof externally of the casing to adjust the relative position of the closures and adjacent baffles to thereby adjust the size of the said orifices.

4. A device as claimed in claim 3 and further characterized in the provision of a guide element within the casing, said guide element having an opening therein, the end of the shaft within the casing being slidably received in the opening of the guide element.

5. A device as claimed in claim 3 and further characterized in that said casing opening is internally threaded, a threaded portion on said shaft threadingly engaging said opening whereby rotation of the shaft is effective to thread the shaft into or out of the casing.

6. An adjustable muffler comprising a casing having an inlet and an outlet, a plurality of spaced apart baffles in the casing, one of said baffles having a relatively small opening and a relatively large opening, the remainder of said baffles having relatively large openings in registry with the relatively small opening of said one baffle, said relatively large openings being provided for the passage of gas through the muffler, said casing having an opening, a shaft extending externally of the casing through said casing opening and through said relatively large registering openings and slidably received in said relatively small opening of said one baffle, sealing means on the casing opening to effect a gas-tight seal, a cap over the external portion of the shaft to effect an additional gas-tight seal, a plurality of closure elements provided on the shaft, each of said closure elements being positioned adjacent one of said relatively large registering baffle openings, said closure elements being related to the respective openings of the adjacent baffles to form orifices through the baffles, said shaft being movable by actuation thereof externally of the casing to adjust the relative position of the closure elements and adjacent baffles to thereby adjust the size of said orifices.

7. An adjustable muffler comprising a casing having an inlet and an outlet, a plurality of spaced apart baffles in the casing, said baffles having registering openings therethrough, a tube received in said registering openings, said tube having openings at the juncture of the tube with each baffle for the passage of gas through the muffler, a rod slidably received in the tube, said rod having a portion of reduced diameter adjacent each of the tube openings, said rod being movable in the tube, an opening in the casing, said rod having a portion extending through said casing opening and terminating externally of the casing, sealing means on the casing opening to effect a gas-tight seal, a cap over the external portion of the rod to effect an additional gas-tight seal, said rod being movable in the tube by actuation of the

5

portion of the rod external of the casing, movement of the rod being effective to adjust the position of the portions of the rod of reduced diameter with respect to the tube openings to thereby adjust the size of the orifices formed by said tube openings and said portions of the rod of reduced diameter.
